UNITED STATES PATENT OFFICE.

JOHN J. SCHILLER, OF CHICAGO, ILLINOIS.

INTERNAL-COMBUSTION ENGINE.

1,414,307.

Specification of Letters Patent. Patented Apr. 25, 1922.

Application filed March 10, 1920. Serial No. 364,702.

To all whom it may concern:

Be it known that I, JOHN J. SCHILLER, a citizen of the United States, and a resident of Chicago, in the county of Cook and State 5 of Illinois, have invented certain new and useful Improvements in Internal-Combustion Engines, of which the following is a full, clear, and exact description.

The invention relates to internal combustion engines.

The object of the invention is to provide an improved slide valve.

The invention consists in the several novel features hereinafter set forth and more particularly defined by claims at the conclusion hereof.

In the drawings: Fig. 1 is a view partly in longitudinal section and partly in elevation of an engine embodying the invention. 20 Fig. 2 is a section taken on line 2—2 of Fig. 1. Fig. 3 is a horizontal section taken on line 3—3 of Fig. 2. Fig. 4 is a detail of one of the removable cylinder-linings. Fig. 5 is a perspective of one of the valves.

25 The engine comprises a crank-shaft 6, a crank-case 7 provided with bearings 8 for the crank-shaft, a body 9, usually a casting, secured to the crank-case by bolts 10 and containing the combustion-chambers 11, 30 cylinders 12 and a water-jacket 13 around the cylinder and combustion-chamber. The invention is illustrated as applied to a four cylinder engine of the four cycle type, but it will be understood that it is applicable to 35 any multi or single cylinder motor and that a description of the invention, as applied to one cylinder, will be sufficient. The engine body is provided with an inlet-port 14 for conducting combustible-fuel into the combustion-chamber 11 and an exhaust-port 15 for the escape of the products of combustion from said chamber. Ignition-means is exemplified by a spark-plug 16 of usual construction. A water-inlet 17 to the water- 45 jacket is connected to one side of the body 9 and an outlet-pipe 18 is secured to the top of said body. The cylinder 12 and walls of the combustion chamber and water jacket are integral. A cylindrical liner 19 forms 50 the working-surface for the slidable piston 20. Said piston is connected by a pitman 21 to a crank on the shaft 6 in usual manner. The liner 19 is provided with a screw-thread 22 for engaging a corresponding 55 thread in the cylindrical wall 12 of the body 9. The body is shouldered, as at 23,

to form a seat for packing 24 which is interposed between the upper end of the liner and the shoulder to form a fluid-tight connection. An advantage in providing the 60 cylinder with a liner 19 is that the liner receives the wear and when it becomes defective, for example, if it becomes scored, it can be unscrewed from the body and repaired or easily replaced. 65

The improved fluid-controlling mechanism comprises inlet and outlet valves substantially the same in construction. Each consist of two cooperating members 25 and 26 both of which are slidable relatively to 70 the body and relatively to each other. A guide-way 27 is formed in the casing for each valve and intersects the port which the valve is designed to control. The outer member 26 is substantially rectangular and 75 fits and slides longitudinally in the guide-way 27. The inner member 25 is slidable in the opening 28 which is formed in member 26 in which it is held by tongue-and-groove connections 29 between the sides of the members respectively. Both members of the valve are adapted to work in the port to be controlled thereby so that the opening and closing of the port will be dependent upon the movement of both members. A groove 80 30 is formed in the inner edge of the top of the member 26 and a rib 31 on the end of member 25 is adapted to enter said groove. This tongue-and-groove form a lapping connection between the members which permits 85 relative movement of the members while the port controlled by the valve remains closed. The outer valve member 26 is operated by a pitman 32 pivoted to a lug 33 on said member and an eccentric 34 on a shaft 35. Member 25 is operated by a pitman 36 pivoted, at 90 37, to said member and an eccentric 38 on shaft 35. The latter is operated from crank-shaft 6 and in suitably timed relation with respect to the piston by a pinion 39 on the 100 crank-shaft and meshing with a gear 40 on the valve-operating shaft 35. The inlet valve is generally indicated by the numeral 41 and the exhaust-valve is generally designated 42. There is a valve-shaft 35 at each 105 side of the crank-casing and these shafts are similarly driven and similarly connected to the valves operated thereby.

While the engine is running, the shaft 35 will be continuously driven and the oppositely disposed eccentrics 34 and 38 on the valve-operating shafts will operate the mem- 110

bers of each valve relatively to one another. Assuming the engine to be at the commencement of an intake-stroke, the exhaust and inlet valves will be closed, as shown in Fig. 5 2. The eccentrics 34 and 38 will then move the outer valve-member 26 upwardly and the inner member 25 of the inlet valve downwardly, and the port 14 will open for the admission of combustible fluid during the 10 intake-stroke and until the valve-members are again lapped at the end of said stroke. During the intake stroke, the members of inlet valve 41 will both continue to move in opposite directions and open and close the 15 admission port 14. During the succeeding compression and power strokes, the inlet and exhaust valves will both be closed. During the succeeding scavenging stroke, the exhaust-valve will open and close. 20 The invention exemplifies an improved valve consisting of simultaneously and relatively movable members which make it possible to provide efficient openings for the passage of fluid as the result of a comparatively short stroke, so that the valve-members 25 may move at comparatively slow speed; and so that they may be operated by eccentrics, if desired; also an improved engine in which provision is made for replacing 30 the operative portion of the cylinders.

The invention is not to be understood as restricted to the details set forth, since these may be modified within the scope of the

appended claims, without departing from the spirit and scope of the invention. 25

Having thus described the invention, what I claim as new and desire to secure by Letters Patent is:

1. In an internal combustion engine, the combination of a cylinder, a casing having a port therein, of a valve comprising a pair of relatively 40 slidable plates provided with coacting margins to open and close the port, said margins being of substantially the same thickness and having their sides disposed in co-incident planes and provided with grooves and integral tongues formed to interfit, and mechanism for simultaneously shifting both of said members in opposite directions to 45 open and close the port.

2. In an internal combustion engine, the combination of a cylinder, a casing having a port therein, of a valve comprising a pair of relatively 50 slidable plates of substantially the same thickness, the casing having a slideway extending transversely of the port, both sides of both plates being formed to engage the sides of the slideway respectively, interfitting integral tongue and 55 groove connections between the sides of the plates, so that one will slide in the other, and mechanism for simultaneously shifting both of the plates in opposite directions to 60 open and close the port.

JOHN J. SCHILLER.
